United States Patent

Des. 239,700
Patented Apr. 27, 1976

239,700

ROTARY CARD FILE

Joseph P. Maruca, Coventry, R.I., and Robert A. Chieda,
Westport, Conn., assignors to Textron Inc., Providence,
R.I.

Filed Aug. 28, 1973, Ser. No. 392,357

Term of patent 14 years

Int. Cl. D19—02

U.S. Cl. D19—76

Fig. 1

Fig. 2

Fig. 3

Fig. 4

FIG. 1 is a right side elevational view of a rotary card file showing our new design with the cover in an open position;

FIG. 2 is a top plan view thereof;

FIG. 3 is a front elevational view thereof; and

FIG. 4 is a right side elevational view with the cover in a closed position.

We claim:

The ornamental design for a rotary card file, as shown and described.
